United States Patent Office

Des. 201,934
Patented Aug. 10, 1965

201,934

HELICOPTER

Luell M. Graham, Fort Worth, Tex., assignor to Bell Aero-
space Corporation, Wheatfield, N.Y., a corporation of
Delaware

Filed Mar. 20, 1964, Ser. No. 79,098

Term of patent 14 years

(Cl. D71—1)

FIGURE 1 is a perspective view of a helicopter embodying my design;

FIGURE 2 is a front elevational view thereof;

FIGURE 3 is a top plan view thereof; and

FIGURE 4 is a side elevational view thereof.

The dominant features of my design reside in the portions shown in full lines on the drawings.

I claim:

The ornamental design for a helicopter, as shown and described.
